UNITED STATES PATENT OFFICE.

JOHN R. BUTLER, OF MONTGOMERY, WEST VIRGINIA, ASSIGNOR OF ONE-THIRD TO
T. B. CHAFFIN, OF MONTGOMERY, WEST VIRGINIA.

RAIL JOINT.

Application filed March 18, 1922. Serial No. 544,762.

To all whom it may concern:

Be it known that I, JOHN R. BUTLER, citizen of the United States, residing at Montgomery, in the county of Fayette and State 5 of West Virginia, have invented certain new and useful Improvements in Rail Joints, of which the following is a specification.

This invention relates to rail joints such as are employed for connecting the abutting 10 ends of railroad rails.

One important object of the invention is to improve the general construction of devices of this character.

A second important object of the invention 15 is to provide an improved form of rail joints wherein a novel arrangement of fish plates is used for connecting a pair of rails.

A third important object of the invention 20 is to provide an improved form of rail joint having a novel arrangement of integral chairs.

A fourth important object of the invention 25 is to provide an improved form of rail joint having a novel construction adapted to produce an extremely solid, rigid and strong joint.

With the above and other objects in view, 30 the invention consists in general of certain novel details of construction and combinations of parts hereinafter fully described, illustrated in the accompanying drawings, and specifically claimed.

In the accompanying drawings, like characters of reference indicate like parts in the 35 several views, and:—

Figure 1 is a perspective view of a rail end as constructed to form the improved joint.

Figure 2 is a side elevation of a rail joint 40 constructed in accordance with this invention.

Figure 3 is a section on the line 3—3 of Figure 2.

Figure 4 is a section on the line 4—4 of 45 Figure 2.

Figure 5 is a section on the line 5—5 of Figure 2.

In the construction of this rail joint the body of the rail is of the usual shape, being 50 provided with the head 10, web 11 and flanges 12, the cross section being preferably the standard cross section for the weight of rail used. The rail body termi-

nates in a squared end 13 and at the end the web 11 is taperingly thickened as at 14 to 55 provide an integral fish plate extending beyond the squared end as at 16, it being observed that the web proper terminates at the squared end while the fish plate portion extends outwardly in such position as to engage against the flat side of the end of an abutting rail web as clearly shown in Figure 5. In like manner the flange on the same side of the rail as the fish plate has its under surface inclined downward to provide a taperingly thickened portion 17 which extends beyond the squared rail end as at 18 to form the under side of a chair portion, the upper side of the chair portion being spaced above this underside as shown at 19 and being carried by the extended fish plate portion. It will be obvious that the portion 19 overlies the upper surface of the rail flange which is inclined upwardly as at 20. Thus the portions 16, 19 and 18 constitute a projecting 70 75 combined fish plate and chair having a groove 21 to receive the end of the flange of the abutting rail.

The taperingly thickened portion 14 of the web 11 and the extended fish plate portion 80 16 are, in each rail, provided with bolt receiving openings 22 wherethrough pass the bolts 23 provided with the usual nuts 24.

From an inspection of the drawing it will be seen that the rail joint thus constructed 85 is of great strength by reason of the connection being made between thick and heavy parts of the rail itself and not by connecting two rails with loose members.

It will also be observed that the taperingly thickened portion provides for a gradual increase in the cross sections of the web and flange of the rail so that the joint may be readily formed by upsetting the rail end and drop forging and that such gradual thickening also eliminates sharp corners tending to develop weaknesses and breakage.

There has thus been provided a simple and efficient device of the kind described and for the purposes specified.

It is obvious that minor changes may be made in the form and construction of the invention without departing from the material principles thereof. It is not therefore desired to confine the invention to the exact form herein shown and described, but it

is wished to include all such as properly come within the scope claimed.

Having thus described the invention, what is claimed as new, is:—

- 5 In a device of the kind described, a rail body having a squared end and provided with a web and a pair of flanges, and a combined fish plate and chair formed integrally with the web and one of the flanges and
- 10 extending beyond said squared end, the web of the rail body being gradually and uniformly thickened from a point spaced from the squared end to said end and the part beyond the squared end being of equal cross

sectional dimensions with the greatest increase of the web to form a fish plate portion, the flange being similarly increased in thickness and similarly having the part beyond the squared end of the same cross sectional dimension as the greatest increase in thickness exteriorly and provided with a groove to receive the flange of an opposed rail end, said groove being tapered to receive the gradually thickened flange whereby said flange is wedged in said groove. 15 20 25

In testimony whereof I affix my signature.

JOHN R. BUTLER.
